Primary Examiner — Alison M Ofstun

Assistant Examiner — Evin F Ershock

(57) **CLAIM**

The ornamental design for a handle for hair brush, as shown and described.

DESCRIPTION

FIG. 1 is a bottom, front and right side perspective view of a handle for hair brush showing my new design;

FIG. 2 is a top, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a first bottom, front and right side perspective view showing the handle for hair brush in an open state;

FIG. 10 is a second bottom, front and right side perspective view showing the handle for hair brush in an open state;

FIG. 11 is a third bottom, front and right side perspective view showing the handle for hair brush in an open state;

FIG. 12 is a bottom, front, and right-side perspective view shown in an environment of use; and,

FIG. 13 is a top, front, and right-side perspective view shown in a second environment of use.

In the drawings, the broken lines illustrate portions of the article, and form no part of the claimed design. In FIGS. 12 and 13, the broken lines illustrating brush heads illustrate environmental subject matter, and form no part of the claimed design.

1 Claim, 13 Drawing Sheets
